UNITED STATES PATENT OFFICE.

JUAN N. SILVA, OF TORONTO, OHIO.

KILN.

Application filed February 20, 1926. Serial No. 89,666.

The present invention relates to certain new and useful improvements in kilns of that general type which are employed for the burning of brick, tile, pottery, and like products, and has for its object to provide a battery of kilns which embodies novel features of construction, whereby the heat from a kiln which is being fired can be used for preheating other kilns instead of being 10 permitted to go to waste.

A further object of the invention is to provide a battery of kilns in which great flexibility is possible in the matter of utilizing the heat from a kiln that is being fired for 15 the preliminary heating or water smoking of other kilns and which, owing to the utilization of this heat which is usually permitted to go to waste, enables the firing of the kilns to be accomplished with a very considerable 20 amount of economy in the amount of coal or fuel used.

The invention also contemplates the provision of a construction which enables a certain amount of control to be exercised over 25 the temperature of the products of combustion which are caused to pass from a kiln which is being fired to another kiln which is being preheated. If the temperature in the preheating kiln is found to be rising too 30 rapidly a certain amount of cold air can be mixed with the products of combustion from the kiln being fired to chill the same the required amount, while if it is found that the 35 temperature of the preheating kiln might advantageously be increased with greater rapidity, the temperature of the products of combustion from the kiln being fired can be boosted by the feeding of auxiliary fuel thereto before it leaves the preheating kiln.

40 Further objects of the invention are to provide a battery of kilns which will operate with a minimum number of stacks and can be inexpensively constructed, which will utilize the heat from the furnaces in the most 45 effective manner and accomplish the burning with a minimum amount of fuel, and which will cause the burning to be accomplished in an even manner and with a minimum percentage of seconds and defective products.

50 While certain specific forms and embodiments of the invention are shown on the accompanying drawings for illustrative purposes, it will be understood that many different arrangements of the kilns are possible 55 and that many modifications and changes can be made in the details of construction

without departing from the spirit of the invention.

For a full understanding of the invention reference is to be had to the following description and accompanying drawings in which,

Figure 1 is a plan view of a battery of six kilns which are constructed and interconnected in accordance with the invention, 65 the kilns themselves being shown in section to illustrate the interior construction thereof.

Figure 2 is a sectional view through a row of three kilns, taken substantially on the line 2—2 of Figure 1.

Figure 3 is a sectional view taken substantially on the line 3—3 of Figure 1.

Figure 4 is an enlarged vertical sectional view through the flue connection between 75 a pair of adjacent kilns, showing the arrangement for conveying heat from the kiln on the right which is preheating to the kiln on the left which is being water smoked.

Figure 5 is a plan view of the cover plates for the connecting members.

Figure 6 is a horizontal sectional view on the line 6—6 of Figure 4.

Figure 7 is a perspective view of the implement for opening and closing the slide valves.

Figure 8 is a vertical sectional view through the furnace of a kiln and the manifold showing the conduit between the floor of the furnace and the manifold.

Figure 9 is a sectional view showing one 90 means for supplying liquid fuel, such as oil, to the heated products of combustion as they pass from one kiln to another kiln, thereby boosting the temperature thereof.

Figure 10 is a similar view showing a 95 possible means for feeding pulverized coal or fuel to the heated products of combustion as they pass from one kiln to another kiln.

Corresponding and like parts are referred to in the following description and indicated on all of the views of the drawings by like reference characters.

The invention is adapted to be used in connection with a battery of kilns, and for convenience in illustrating the idea of the invention a battery comprising six kilns is shown on the drawings, although it will be understood that the battery may comprise a greater or a less number of kilns, as desired, and that the arrangement of the kilns may 105 be varied. For convenience the six kilns are 110 designated by the respective characters A, B,

C, D, E and F. The structure of each of the kilns comprises the usual circular wall portion 1 and arched dome 2. A series of furnaces 3 is provided in the wall of each kiln. 5 The furnaces may be of any suitable or approved type and are arranged at intervals around the kiln. The interior of the kiln is provided with a bag wall 4 for each of the furnaces so that the heated products of combustion from the furnaces are conducted upwardly to the top of the kiln by the bag walls when the kiln is being fired.

Arranged under the central portion of the floor of each kiln is a pit 5 and floor flues 6 10 radiate from this pit under the floor of the kiln said flues communicating with the kiln through the openings 7 in the floor. The floor flues 6 have a novel formation, being formed with bottom walls which incline downwardly toward the pit 5. This is advantageous in that dust and dirt which would otherwise accumulate in the flues and tend to clog the same will be deflected into the bottom of the pit 5 from which it can be readily 15 cleaned at proper intervals of time. Each of the kilns is provided with a suitable door opening 8, through which access can be had to the kiln for conveying the articles to be burned into and out thereof. The door openings 8 may be bricked up or closed in any 20 suitable manner during the burning of the kiln. The furnace openings can be closed by suitable plates 9 applied to the exterior of the kiln when the furnaces are not in use and it is desired to close these openings. 25 These plates 9 are shown in position on kilns B, C and E of Fig. 1.

The central pits 5 of the kilns A, B and C are connected by the flues 10, as are also the 30 central pits of the kilns D, E and F. A somewhat similar flue 11 connects the central pits 5 of the kilns A and D and these flues 10 and 11 provide for the passage of the heated products of combustion from one kiln to another kiln. A manifold 12 extends around each of the kilns at the base thereof, being shown on the drawings as having the form of an underground tunnel. Branch conduits 13 extend inwardly 35 and upwardly from each of the manifolds 12 and terminate at the bottom of the furnaces 3 in manholes which may be closed by the manhole covers 14. These covers 14 can be quickly placed in position or removed 40 therefrom and are placed in position when it is desired to cut off communication between the manifold and the interior of the kiln. The manifolds 12 need not be complete circles and the portion of each manifold 45 between the branch conduits 13 on opposite sides of one of the door openings 8 of the kiln is shown as omitted.

An exhaust tunnel 15 extends between the two rows of kilns and a fan 16 is provided 50 for forcing the products of combustion

from the end of this exhaust tunnel into the stack 17. A single stack is sufficient for an entire battery of kilns and the cost of erecting a separate stack for each kiln or small group of kilns is avoided. This results in 55 quite a considerable saving, because the cost of the stack is a very material part of the cost of erecting a kiln of the usual construction. The exhaust tunnel 15 is formed with a branch 15^a leading toward each of the kilns. These branches terminate in manholes 18 which are located in a spaced relation to companion manholes 19 for the manifolds 12. These manholes are closed by suitable manhole covers when they are not 60 in use, although when it is desired to connect one of the manifolds to the exhaust tunnel the covers of the corresponding manholes 18 and 19 are removed and a goose neck 50 placed in position to connect the 65 manholes, the two arms of the goose neck being inserted in the manholes. The suction from the stack and exhaust fan 16 then acts through the goose neck 50 to exhaust the air and products of combustion from the 70 manifold and kiln.

Each of the kiln connecting flues 10 communicates at its middle portion with a well 20 which extends upwardly to the surface of the ground where it is provided with a cover plate 21, said cover plate having an opening 22 therein which is normally closed by a removable cover. Opposite sides of the well 20 are formed with guide-ways within which the gate valves 23 are slidably mounted. These gate valves are adapted to be moved downwardly to close the ends of the flues 10 and cut off communication between the well and the ends of the flue. The gate valves can be operated in any suitable manner and either are locked in an open or closed position or constructed to be held by friction in an adjusted position. As shown on the drawings, each of the gate valves is formed at the upper end thereof with an opening 24 which can be engaged by the hooked end of a suitable hand tool 25 such as that illustrated by Figure 7, to open or close the valves.

On each side of the well 20 are manholes 26 which extend upwardly from the manifolds 12 of the respective kilns. Cover plates 27 are provided for the manholes 26, said cover plates having openings 28 therein which are normally closed by removable covers. The well 20 can be connected with either of the manholes 26 by removing the covers from the openings in the respective cover plates and inserting the arms of a goose neck 50 in the openings, as shown by Figure 4. By this means the hot air and products of combustion can be carried from the manifold 12 of one kiln to the flue 10 of an adjacent kiln, or vice versa. On the other hand when the gate valves 23 are both 125

opened and the opening 24 at the top of the well closed, the hot air and products of combustion will pass directly from the pit 5 of one kiln through the flues 10 to the pit 5 of the adjacent kiln.

The flue 11 which extends between the kilns A and D is in communication with the wells 29 which are located adjacent the manifolds 12 of the respective kilns. Gate valves 30 are provided in the side of each well 29 toward the adjacent kiln, said gate valves being similar to the gate valves 23 and being adapted to be operated in the same manner. The manifolds 12 of the kilns are provided with manholes 26 arranged adjacent to the wells 29. The manholes and wells are provided with cover plates having openings therein adapted to receive a goose neck 50, just as previously described in connection with the wells 20 and manholes 26. When the valves 30 are both opened and the openings in the cover plate closed the flue 11 establishes a direct connection between the pits 5 of the kilns A and D. On the other hand, either of the gates can be closed and the corresponding goose neck placed in position to establish communication between the flue 11 and the manifold 12 of either of the kilns A or D.

Let it be assumed that the kiln A is being burned and that all of the furnaces 3 thereof are in operation, and that the kiln D has been filled and is ready for preheating. Ordinarily the heat and products of combustion from a kiln which is being fired are conveyed directly to a stack and permitted to pass up the stack without any use being made thereof. However, with the present arrangement the gate valves 23 for the flues 10 between the furnaces A and B would be opened and the openings 28 and 24 closed. The furnace openings 3 of the kiln B would be closed by the plates 9, and the manifold 12 of the kiln B would be connected to the exhaust tunnel 15 by placing a goose neck 50 in engagement with the manholes 18 and 19 of the said kiln. With this arrangement the products of combustion from the burning furnaces 3 of the kiln A would be carried to the top of the kiln by the bag walls 4 thereof and would then circulate downwardly through the kiln to the floor openings 7, passing through the floor openings into the floor flues 6 which convey them to the pit 5. From the pit 5 of the kiln A the hot air and products of combustion pass directly to the pit 5 of the kiln B through the flues 10. The hot air and products of combustion then circulate upwardly through the kiln B to the top thereof and thence downwardly through the bag walls of the kiln B to the bottom of the furnaces 3 of the said kiln, whence they pass through the branch conduits 13 to the manifold 12.

The branch conduits 13 of the manifold

12 for the kiln A would be closed by the manhole covers 14, while the said manhole covers 14 for the kiln B would all be removed. The manifold 12 of the kiln B, as previously stated, is connected by 70 the goose neck 50 to the corresponding branch 15^a of the main exhaust tunnel 15, so that the combined action of the stack and exhaust fan 16 will produce a suction in the manifold 12 of the kiln B to draw 75 the hot air and products of combustion into the kiln B from the kiln A. It will also be obvious that if the kiln D were ready for preheating instead of the kiln B, proper adjustment could be made for carrying the 80 products of combustion from the kiln A through the kiln D before permitting them to enter the main exhaust tunnel and be conveyed thereby to the stack.

While burning the kiln A and preheating 85 the kiln B it might happen that the kiln C had been filled and was ready to be water smoked. Under such conditions no connection would be established between the manifold 12 of the kiln B and the main 90 exhaust tunnel, but the hot air and products of combustion from the said manifold 12 of the kiln B would be caused to pass through a goose neck 50 into the well 20 between the kilns B and C. The gate valves 95 23 of this well 20 would be adjusted to cut off communication between the said well and the flue 10 of the kiln B and establish communication between the said well and the flue 10 of the kiln C. The warm air and 100 products of combustion would thus circulate upwardly through the kiln C just as they have previously done through the kiln B, with the result that the contents of the kiln C will be water smoked. Communication 105 would be established between the manifold 12 of the kiln C and the corresponding branch 15^a of the main exhaust tunnel 15 by means of a goose neck 50 so that the combined action of the stack and exhaust fan 110 110 would serve to draw the products of combustion through the kilns.

It will be noted that in the kiln which is being fired the products of combustion pass downwardly through the contents of the kiln so that the contents are heated from the top downwardly, while in the kilns which are being preheated or water smoked the products of combustion circulate in a reverse direction, namely, from the bottom to the top of the kilns, so that during the preheating and water smoking processes the contents of the kilns are heated from the bottom upwardly. The contents of a kiln may thus be thoroughly preheated before 120 fires are started in the furnaces 3 thereof and when the fires are started the bottom of the kiln is already thoroughly heated so that the usual resistance to the passage of the draft through a cold kiln is avoided, and 125 130

1. there will be less possibility of overburning the top portion of the contents of the kiln in heating up the bottom of the kiln. Owing to the fact that the contents of the kiln may be thoroughly preheated before the furnaces of the kiln are started, the burning can be effected with a very material saving in the amount of fuel used.

At times it may be possible that the temperature in the kiln which is being preheated will rise too rapidly and, if this is found to be the case, the cover for the opening 22 at the top of the well 20 between the kiln which is being burned and the kiln which is being preheated can be partially opened to permit the entrance of a sufficient amount of cold air into the well to lower the temperature of the hot air and products of combustion so that the preheating will proceed at the proper rate. On the other hand, there may be times when it would be advantageous to hasten the preheating by a more rapid rise in temperature than that which is brought about by the hot air and products of combustion from the kiln being fired. Under such conditions the present invention contemplates a means for boosting the temperature of the air and gases as they pass from one kiln to another kiln, so that the desired higher temperature can be produced in the second kiln by the use of a slight additional amount of fuel.

A liquid fuel such as oil may be used for this purpose. As shown by Figure 2, an oil supply pipe 31 extends along the row of kilns and has branch pipes 32 which extend through the tops of the kilns, and branch pipes 33 which extend downwardly above the wells 20. These branch pipes are provided with valves 34 by means of which the flow of liquid fuel can be controlled.

The kilns may each be provided at the top thereof with the usual vent opening into which the lower ends of the branch pipes 32 extend. When the kilns are in operation these openings may be closed by sectional blocks 60 which fit over the same and are applied to the branch pipes 32 from opposite sides thereof, being correspondingly notched to receive the said pipes. When it is desired to boost or increase the temperature within the kiln the valve 34 can be partially or entirely opened to permit the feeding of auxiliary fuel to the heated products of combustion at the top of the kiln.

The covers for the openings 22 in the cover plate 21 for the wells 20 have central openings therein which are normally closed by a removable plug 35. When this plug is removed a detachable extension 36 may be applied to the end of the corresponding branch pipe 33 and the lower end of the extension caused to project through the opening in the manhole cover as shown by Figure 9. The oil or liquid fuel may thus be

permitted to drop into the manhole where it will be consumed and cause a rise in the temperature of the air and products of combustion as they pass from one kiln to the next kiln. Instead of liquid fuel a gaseous fuel might be supplied to the wells in this same manner. The oil or gas can also be fed to the top of the kilns through the branch pipes 32 if such is desired.

In Figure 10 a possible arrangement for supplying pulverized coal to the manhole is shown. A hopper 37 which is supported upon a suitable stand 38 has a discharge neck 39 which can be inserted through the opening in the manhole cover as illustrated. A suitable valve can be provided for controlling the flow of pulverized coal through the discharge neck, and the small quantity of pulverized coal which is dropped into the well will be burned and bring about an increase in the temperature of the air and products of combustion which are passing from one kiln to another kiln. By the use of a small amount of auxiliary fuel the preheating process may be expedited and the contents of the second kiln burned to a greater extent before starting the furnaces in the second kiln than would otherwise be possible.

Should it happen that one of the next kilns is not ready for preheating when a certain kiln is fired, the valve 23 controlling communication between the well 20 and the flue 10 of the next kiln is closed and a goose neck 50 placed in position to carry the products of combustion from the well 20 to the manifold 12 of the next kiln. This manifold 12 of the next kiln is connected through another goose neck 50 with a branch of the main exhaust tunnel 15, so that the hot air and products of combustion pass through the manifold 12 of the next kiln to the exhaust tunnel without passing through the interior of the next kiln which is not ready for preheating.

The construction and arrangement is such as to necessitate a minimum amount of underground tunnels and manifolds, and at the same time provide great flexibility in the connections which are possible between the various kilns. Provision is made for the continuous, direct or semi-continuous firing of the kilns, and the utilization of the products of combustion from a kiln which is being fired to preheat and water smoke other kilns is conducive to economy in the use of fuel and enables the kilns to be burned with much less fuel than would otherwise be required were the products of combustion carried directly to the stack without being utilized for the preheating of other kilns.

Having thus described my invention what I claim as new and desire to secure by Letters Patent is,

1. The combination with a battery of 130

kilns, of means for circulating the products of combustion through the kilns, and means for modifying the temperature of the products of combustion as they are being circulated.

5 2. The combination with a battery of kilns, of means for conveying the heated products of combustion from one kiln to another kiln, and means for varying the temperature of the products of combustion as they pass between the kilns.

10 3. The combination with a battery of kilns, of means for conveying the heated products of combustion from one kiln to another kiln, and booster means for increasing the temperature of the products of combustion as they pass from kiln to kiln.

15 4. The combination with a battery of kilns, of means for conveying the heated products of combustion from one kiln to another kiln, and means for feeding auxiliary fuel to the products of combustion for increasing the temperature thereof as they pass from kiln to kiln.

20 5. The combination with a battery of kilns, of means for conveying the heated products of combustion from one kiln to another kiln, and means for feeding regulated quantities of auxiliary fuel to the products of combustion to increase the temperature as they pass from kiln to kiln.

25 6. The combination with a battery of kilns each of which has a manifold and a floor pit, of flues connecting the floor pits of adjacent kilns, and means for placing said flues in communication with the manifolds.

30 7. The combination with a battery of kilns each of which has a manifold and floor pit, of flues connecting the floor pits of adjacent kilns, valves for the flues, and means for placing said flues in communication with the manifolds.

35 8. The combination with a battery of kilns each of which has a manifold and floor pit, flues connecting the floor pits of adjacent kilns, valves for the flues, and detachable conduit members for selectively connecting the flues to the manifolds as desired.

40 9. The combination with a pair of kilns each of which has a floor pit and manifold, of a well, kiln connecting flues extending from the pits of the kilns to the well, valves controlling communication between the flues and the well, and means for establishing communication between the well and one of the manifolds.

45 10. The combination with a pair of kilns each of which has a manifold and a floor pit, of a well, kiln connecting flues extending from the floor pits to the well, valves controlling communication between the said flues and the well, and means for selectively establishing communication between the well and either of the manifolds.

50 11. The combination with a pair of kilns

each of which has a manifold and a floor pit, of a well, kiln connecting flues extending from the floor pits to the well, valves controlling communication between the flues and the well, a removable closure for the well, and means for selectively establishing communication between the well and either of the manifolds when the said closure is removed.

55 12. The combination with a pair of kilns each of which has a manifold and floor pit, of a well, kiln connecting flues extending from the floor pits to the well, valves controlling communication between the flues and the well, a removable closure for the well, manholes for the manifolds, and a goose neck member adapted to selectively connect the well with the manhole of either of the manifolds when the cover is removed.

60 13. The combination with a pair of kilns, a flue connecting the kilns for carrying the products of combustion from one kiln to another kiln, and means for boosting the temperature of the products of combustion as they pass through the flue.

65 14. The combination with a pair of kilns, of a flue connecting the kilns for carrying the products of combustion from one kiln to the other kiln, and means for feeding auxiliary fuel to the flue for boosting the temperature of the products of combustion as they pass through the flue.

70 15. The combination with a pair of kilns, a well, kiln connecting flues extending from the well to the respective kilns, a removable cover for the well, and means for supplying auxiliary fuel to the well for boosting the temperature of the products of combustion as they pass through the flues from one kiln to the other kiln.

75 16. The combination with a pair of kilns, a flue connection between the kilns for carrying the products of combustion from one kiln to the other kiln, means for feeding auxiliary fuel to the products of combustion as they pass from one kiln to the other kiln, and means for feeding auxiliary fuel to the interior of the kilns.

80 17. A kiln provided in the side walls thereof with the usual furnaces, and means independent of the furnaces for feeding auxiliary fuel to the interior of the kiln.

85 18. The combination with a battery of kilns, each of which has a manifold and floor pit, of flues extending between floor pits of adjacent kilns, means for placing the said flues in communication with the manifolds at will, a main exhaust tunnel, and means for placing the main exhaust tunnel in communication with a selected manifold.

90 19. The combination with a battery of kilns each of which has a manifold and floor pit, of flues connecting the floor pits of the kilns, means for placing the flues in communication with selected manifolds, a main

exhaust tunnel having branches extending toward the manifolds of the various kilns, uniformly spaced manholes for the branches and manifolds, removable covers for the manholes, and goose necks adapted to connect the manholes when the covers are removed.

20. The combination with a battery of kilns, each of which has a manifold and floor pit, wells between the kilns, kiln connecting flues extending between the wells and the floor pits of the kilns, a main exhaust tunnel having branches extending toward the manifolds of the respective kilns, uniformly spaced manholes for the said branches and manifolds, a second set of manholes for the manifolds arranged adjacent the wells, removable covers for the wells and manholes, and interchangeable goose necks selectively connecting the wells to desired manifolds and connecting one of the manifolds to a branch of the main tunnel.

21. The combination with a battery of kilns each of which has a manifold and floor pit, of wells between the kilns, kiln connect-

ing flues extending from the wells to the floor pits of the kilns, valves controlling communication between the wells and the flues, a main tunnel, manholes arranged adjacent the various manifolds and in communication with the main tunnel, manholes for the manifolds arranged adjacent to the wells and manholes of the main tunnel, removable covers for the wells and manholes, and detachable goose neck elements adapted to connect a selected well to a manifold and to connect a selected manifold to the main tunnel.

22. The combination with a kiln, of furnaces for heating the kiln, and auxiliary means independent of the furnaces for boosting the temperature of the kiln.

23. The combination with a kiln, of a furnace from which the products of combustion are caused to pass through the kiln, and means independent of the furnaces for supplying auxiliary fuel to the products of combustion to boost the temperature thereof.

In testimony whereof I affix my signature.

JUAN N. SILVA.
